POCKET CASE

Filed Oct. 4, 1923

INVENTOR
Leopold George Stanley
BY Edward S. Beach

ATTORNEY

UNITED STATES PATENT OFFICE.

LEOPOLD GEORGE STANLEY, OF NEW YORK, N. Y., ASSIGNOR TO STANLEY & STANLEY, INC., OF NEW YORK, N. Y., A CORPORATION OF NEW YORK.

POCKET CASE.

Application filed October 4, 1923, Serial No. 666,482.

To whom it may concern:

Be it known that I, LEOPOLD GEORGE STANLEY, a subject of the King of Great Britain, resident of New York city, in the 5 county of New York and State of New York, have invented certain new and useful Improvements in Pocket Cases, of which the following is a specification.

This invention relates to improvements in 10 pocket cases. It is particularly intended for use as a cigarette holder, but may be used for other purposes.

The object of the invention is to produce, preferably out of leather, at an economic 15 manufacturing cost, a case in which cigarettes or other articles carried may have their upper ends or portions freely exposed and readily accessible and at the same time protected from injury in the closed case.

20 In the accompanying drawings forming a part hereof and illustrating my invention:

Fig. 1 is a perspective view of my new case with its cover flap partially open. Fig. 2 is a vertical section of the case closed at a 25 line corresponding to line 2—2 of Fig. 1.

Fig. 3 is a transverse section of what is shown in Fig. 2 at line 3—3 of Fig. 2.

Fig. 4 is an end view of the case closed.

Fig. 5 is a perspective view of the cigarette or article container detached and shown spaced apart from a bottom forming strip and case side spacing member.

In the drawings, the case is made up of 35 four main members which when of leather are cemented together in the completed assemblage. These members are the outer case; the article holder; means for spacing and bracing apart the flexible sides of the article holder; and the bottom strip spacing member.

The outside casing comprises laterally spaced apart front and back sides, respectively indicated by 1 and 2. These members are marginally sewed together at 3 along the 45 bottom and at each end of the casing. The sides are initially formed into a laterally bulging shape whereby in the assemblage the front and back sides, while parallel in their main extent, severally swell outwardly 50 from their stitched, marginal portions. The back side 2 is extended upwardly into a somewhat narrowed portion which forms a freely bendable cover flap 2^a, dimensioned to be folded over the front side of the casing and

to be secured in closed position or in any 55 suitable manner, or not secured at all. As shown, the free portion of the cover flap may be tucked in a transverse loop 4 to hold it in place or may be secured to the front wall of the casing by the complementary 60 fastener members 4^a and 4^b. The front side is upwardly extended into a marginal, forwardly bendable flap 1^a which forms a side guard for the upper ends of the cigarettes or other articles contained in the holder. It 65 is opposed, when folded upright, to a back, marginal portion 2^b of the cover flap which forms a back guard for the exposed ends of the articles carried in the holder when the cover flap is folded down. The cover 70 flap is bendable from end to end, this bend forming the top edge of the case when it is closed.

The holder or container for cigarettes or other articles is made up of two spaced 75 apart pieces of leather 5 forming the front and back sides of the container. These sides are shaped to stand away one from another, their under edges are flexible and their upper edges 7 are transversely aligned one 80 with another throughout their length and are curved upwardly at their ends providing the holder with upstanding, projecting, end portions 8 above the general level of the upper edges 7 between the ends 8. The end 85 margins of the front and back sides 5 are stitched together at 9.

In order to stiffen the container between its front and back sides and thus prevent 90 injury to the cigarettes by accidental pressure on the sides of the case, these sides are braced apart by a leather brace which also ties the sides 5 together. The brace extends part way from the top edges 7 of the container to the under or bottom edges thereof. 95 The brace is made up of two strips of bendable leather, each given a lengthwise troughed form in the bracing assemblage. The bottom wall 10 of one troughed member has parallel, bendable side flanges 11 and 12. 100 The bottom wall 13 of the other troughed member is glued to the wall 10 and has parallel, flange forming portions 14 and 15. The front, flange forming portions 11 and 15 are carried forwardly through a slot 7^a in the front wall 5 and the back flanges 12 and 14 are carried through a similar slot 7^a 105 in the back wall 5, the cemented together

walls 10 and 13 being vertically mounted within the chamber of the container. The flange forming portions 11 and 15 are bent over on the outer side of one of the sides 5 and cemented thereto; and the flange forming portions 12 and 14 are bent over on the outer surface of the other side 5 and cemented thereto. The vertical, interior walls 12 and 13 divide the holder into two chambers and serve to brace the sides 5 apart. The holder is dimensioned to be slipped tightly into the chamber of the main casing and to be cemented therein with the unclosed bottom side of the container bearing on the bottom forming and spacing strip 16 which is cemented in place in the bottom portion of the main casing above the converging, under marginal edge of the casing. The strip 16 is flat and forms the flat bottom for the container on which the under ends of the cigarettes may rest. The holder or container is also so dimensioned that its edges 7 in the assemblage stand above the bending lines of the front and back guard portions of the main casing. By this construction the holder or container may be filled with cigarettes, the upper end portions of which will be accessible above the edges 7 and in line between the upstanding projections 8. When the front guard flap 1^a is vertical and parallel with the back guard flap portion 2^x in its vertical position and the cover flap is in position to close the case, the exposed, upper portions of the cigarettes will be laterally guarded and kept from injury. The upward projections 8 serve as guards for the end cigarettes in a line of cigarettes placed in the holder, the flaps 1^a and 2^x protect the line of cigarettes laterally and the tops of the projections or horns 8 serve to prevent the fold of the cover flap at y—y being depressed at the upward, exposed ends of the cigarettes or other articles which are not intended to project upwardly above the aligned tops of the horns 8. The brace and tie construction divides the case into chambers and forms a gusset or partition between the chambers and is so located that with cigarettes of the length intended to be put in each chamber, the cigarettes in the one chamber cannot fall lengthwise into the bottom of the adjacent chamber when the cigarettes in such adjacent chamber are exhausted.

What I claim is:

1. A pocket case made up of a main casing having spaced apart sides; a bendable cover flap comprising a back guard flap; a bendable front guard flap; a holder having spaced apart sides provided with upwardly projecting end portions and mounted with its sides between the sides of the main casing with said projections extending above the under portions of the guard flaps; the guard flaps being dimensioned and positioned opposely to cover the front and back spaces formed by and between the said upward projections, the guard flaps serving to protect laterally the sides of articles contained in the holder and the projections serving to protect the end members of articles contained in the holder and to keep the cover flap from being crushed down on the upper ends of such contained articles; a flat bottom spacing strip fixed in an under portion of the main casing and forming a bottom wall for the holder; and between the sides of the holder, vertical spacing and bracing means comprising a piece of sheet material mounted through opposed vertical slits in the side walls of the holder and having its ends flat-wise and exteriorly on and fixed to opposed sides of the holder.

2. A pocket case made up of a main casing having spaced apart sides; a bendable cover flap comprising a back guard flap; a bendable front guard flap; a holder having spaced apart sides provided with upwardly projecting end portions and mounted with its sides between the sides of the main casing with said projections extending above the under portions of the guard flaps; the guard flaps being dimensioned and positioned opposely to cover the front and back spaces formed by and between the said upward projections, the guard flaps serving to protect laterally the sides of articles contained in the holder and the projections serving to protect the end members of articles contained in the holder and to keep the cover flap from being crushed down on the upper ends of such contained articles; the said holder further comprising a pair of lengthwise troughed pieces cemented together back to back and having their ends at one side of the holder projected through such side, reversely bent and cemented flat-wise on the outward surface thereof.

3. A pocket case made up of a main casing having spaced apart sides; a bendable cover flap comprising a back guard flap; a bendable front guard flap; a holder having spaced apart sides provided with upwardly projecting end portions and mounted with its sides between the sides of the main casing with said projections extending above the under portions of the guard flaps; the guard flaps being dimensioned and positioned opposely to cover the front and back spaces formed by and between the said upward projections, the guard flaps serving to protect laterally the sides of articles contained in the holder and the projections serving to protect the end members of articles contained in the holder and to keep the cover flap from being crushed down on the upper ends of such contained articles; a fixed partition between the ends of the holder positioned to maintain upright contained articles of a length less than the

length of a holder chamber, the partition comprising two vertical, lengthwise troughed members having flat, contacting portions within the chamber of the holder, 5 each end of these contacting portions passing through a vertical slot in a side wall of the holder, and each of the partition

forming members having a flange flat-wise united with an exterior surface of the holder.

Signed at New York city in the county of 10
New York and State of New York, this 29th
day of August, A. D. 1923.

LEOPOLD GEORGE STANLEY.
